UNITED STATES PATENT OFFICE.

CHESTER H. CARNES, OF TRINIDAD, COLORADO.

EYEGLASS-GUARD.

No. 828,924.

Specification of Letters Patent.

Patented Aug. 21, 1906.

Application filed February 26, 1906. Serial No. 303,091.

To all whom it may concern:

Be it known that I, CHESTER H. CARNES, a citizen of the United States, residing at Trinidad, in the county of Las Animas and State of Colorado, have invented certain new and useful Improvements in Eyeglass-Guards, of which the following is a specification.

My invention contemplates certain new and useful improvements in guards for eyeglasses; and the primary object of the invention is to provide an improved device of this character which will admit of a wide range of adjustability, which is a desideratum in the optician's and oculist's profession, and which will be securely held in its different adjusted positions without danger of becoming loose and without any liability of the position becoming accidentally changed.

My invention consists, essentially, of an eyeglass-guard comprising a longitudinally-slotted nose piece or plate preferably channeled to receive the rubber, cork, or similar pad, as the case may be, the surface adjacent the slot being corrugated, and an attaching arm or shank designed for attachment to a stud-box on the eyeglass and axially adjustable at one end on a bolt, the head of which is arranged for engagement with the corrugated surface of the nose-piece, while the shank thereof extends through the slot and is designed to receive the clamping members for holding the attaching-arm at different angular positions with respect to the nose-piece.

The invention also comprehends, broadly, a device of this character embodying in combination a longitudinally-slotted nose-piece and an attaching-arm longitudinally and axially adjustable in the slot of the nose-piece.

The invention further consists in certain details of construction and arrangements and combinations of the parts hereinafter fully described and claimed.

For a full description of the invention and the merits thereof and also to acquire a knowledge of the details of construction of the means for effecting the result reference is to be had to the following description and accompanying drawings, in which—

Figure 1 is a perspective view of a pair of eyeglasses embodying the improvements of my invention. Fig. 2 is a perspective view of the guard detached. Fig. 3 is a similar view with parts of the guard separated. Fig.

4 is a vertical section through the nose-piece. Fig. 5 is a horizontal section of the same. Fig. 6 is a face view of one of the clamping parts. Fig. 7 is a detail view illustrating a modification.

Corresponding and like parts are referred to in the following description and indicated in all the views of the drawings by the same reference characters.

Referring to the drawings, the numeral 1 designates the lenses of a pair of eyeglasses provided with the improvements of my invention. 2 designates the stud-boxes thereof, and 3 designates the bridge or spring.

My improved guard comprises a nose-piece 4, which is preferably channeled or provided with inturned or beveled side edges 5 for the reception and retention of the cork, rubber, or similar pad 6. In the present instance the nose-piece 4 is in the form of a rectangular plate, and it is provided with a longitudinal slot 7. On its inner or channeled side the nose piece or plate 4 is provided with one or more rows or series of transverse corrugations 8, the same preferably bounding both sides of the slot 7. A bolt 9 is provided with a head 10, designed to fit within a longitudinally-extending recess 11 in the corrugated side of the plate 4 and, as shown, is held from turning therein owing to the fact that the head and recess are correspondingly shaped. In the present embodiment the head is shown as being rectangular or with flat side edges; but, as illustrated in Fig. 7, it may be curved to correspond to the general shape of the plate 4 when the latter is curved so as to meet the different requirements for differently - formed nose pieces or guards. The head 10 of the bolt 9 is corrugated on one side, as shown at 12, and its corrugations intermesh with the corrugations 8 of the plate 4. The shank 13 of the bolt extends into and through the slot 7 to the other side of the plate 4 and is preferably threaded, as shown. One member 14 of a clamping device, which in the present instance is substantially of disk form, is provided at diametrically opposite points with lugs 15, that are designed to be bent inwardly and take into the slot 7. The inner face of this member of the clamping device is radially notched or serrated, as indicated at 16.

The complementary member 17 of the clamping device is interposed between the member 14 and the outer surface of the plate 4 and is correspondingly radially notched, as

indicated at 18. Both members 14 and 17 of the clamping device are provided with concentric apertures 19, which are accommodated on the shank of the bolt 9; but said apertures and shank at that point are preferably devoid of threads. Secured to the member 17 of the clamping device and preferably an integral part thereof is an attaching arm or shank 20, intended to secure the nose-piece 4 to the stud-box 2 of the eyeglasses in any suitable manner. In the present instance the ordinary square apertured head 21 is utilized for this purpose. A binding-nut 22 is mounted on the outer threaded end of the shank of the bolt 9, so as to bind the two members of the clamping device together, and said nut is preferably formed at diametrically opposite points with recesses 23 for the reception of a pair of tweezers or some 20 similar tool acting in the nature of a spanner-wrench to screw the nut on the shank and unscrew it therefrom.

From the foregoing description, in connection with the accompanying drawings, it is evident that the attaching device 20 may be slid longitudinally with respect to the nose-piece or plate 4 and that it may also be adjusted axially with relation thereto, the binding-nut 22 being slightly loosened to allow 30 sufficient play of the parts. The required angular and longitudinal adjustments of the parts having been effected to a nicety, so that the eyeglasses may be adjusted to a person's nose in the proper manner, it is evident that 35 the parts may be securely held in their adjusted position by simply screwing up the bind-nut 22. Hence it will be seen that I have provided a simple device of this character possessing to a marked degree efficiency 40 of operation, in that a nicety of adjustment may be effected readily and the parts securely held in their adjusted position without liability of accidental derangement.

Having thus described the invention, what 45 is claimed as new is—

1. An eyeglass-guard, comprising a nose-piece provided with a longitudinal slot, a bolt designed to be secured to said nose-piece at different longitudinal positions thereon and 50 provided with a shank extending through said slot, an attaching-arm mounted on the shank of the bolt and arranged to turn axially thereon, a clamping member arranged for guiding engagement by said slot, and 55 means for binding said clamping member against the attaching-arm as and for the purpose set forth.

2. An eyeglass-guard comprising a longitudinally-slotted nose-piece provided with a 60 longitudinal recess, a bolt provided with a head mounted to move longitudinally in said recess and engaging the walls of the recess in such a manner as to prevent the head from

turning, said bolt having a shank extending through the slot of the nose-piece, an attaching-arm mounted to turn axially on the shank of the bolt and means for clamping said arm on the shank of the bolt at different axial adjustments. 65

3. An eyeglass-guard comprising a longitudinally-slotted nose-piece, a bolt mounted to move longitudinally on said nose-piece and provided with a shank extending through said slot, an attaching-arm provided with a notched outer face at one end and mounted 70 to turn axially on the shank of the bolt at such end, and a clamping member having a correspondingly-notched face designed to mesh with the face of the attaching-arm and provided with a tang or lug fitting in said slot, 75 and a binding-nut threaded on the outer end of the shank of the bolt, as and for the purpose set forth. 80

4. An eyeglass-guard, comprising a longitudinally slotted and channeled plate provided with a recess and a roughened surface, a bolt provided with a head shaped corresponding to the recess and fitted to move longitudinally therein but prevented from turning axially therein, the head of the bolt being 85 provided with a roughened surface designed to engage the roughened surface of the plate and said bolt provided with a shank extending through said slot and provided with a threaded outer end, a clamping member provided with a notched inner face and with lugs taking into the slot, the said member being apertured to receive the shank of the bolt, an attaching-arm interposed on the shank of the bolt between said clamping member and the outer face of the said plate and provided with notches designed to engage the notches 90 on the clamping member and a binding-nut 95 designed to be screwed on the outer end of the shank of the bolt. 100

5. An eyeglass-guard, comprising a longitudinally-slotted plate, a bolt mounted to move longitudinally on said plate and provided with a shank extending through the slot of the plate, a clamping member provided with lugs designed to fit in said slot whereby to prevent said member from turning, an attaching-arm interposed between 105 said clamping member and the plate, both the clamping member and the attaching-arm 110 receiving the shank of said bolt, and means for binding the clamping member and attaching-arm against the said plate at different angular or axial positions. 115

In testimony whereof I affix my signature 120 in presence of two witnesses.
